The ornamental design for an element for a toy building set, as shown and described.

DESCRIPTION

FIG. 1 is a top perspective view of an element for a toy building set showing my new design;

FIG. 2 is a front elevational view thereof;

FIG. 3 is a right side elevational view thereof, the left side elevational view being a mirror image;

FIG. 4 is a rear elevational view thereof;

FIG. 5 is a top plan view thereof; and,

FIG. 6 is a bottom view thereof.
